DESIGN FOR A PHOTOGRAPHIC VIEWING APPARATUS

Alvin E. Schubert, Rochester, N. Y., assignor to Eastman Kodak Company, Rochester, N. Y., a corporation of New Jersey

Application December 2, 1939, Serial No. 88,644

Term of patent 14 years

To all whom it may concern:

Be it known that I, Alvin E. Schubert, a citizen of the United States, residing at Rochester, in the county of Monroe and State of New York, have invented a new, original, and ornamental Design for a Photographic Viewing Apparatus, of which the following is a specification, reference being had to the accompanying drawing, forming part thereof and in which:

Fig. 1 is a front perspective view; and
Fig. 2 is a side elevation of a photographic viewing apparatus, showing my new design.

I claim:

The ornamental design for a photographic viewing apparatus, as shown.

ALVIN E. SCHUBERT.
